DESIGN.

L. KAHN & R. THIEM.

STOVE.

No. 17,172.

Patented Mar. 8, 1887.

UNITED STATES PATENT OFFICE.

LAZARD KAHN AND RUDOLPH THIEM, OF HAMILTON, OHIO, ASSIGNORS TO
F. & L. KAHN & BROTHERS, OF SAME PLACE.

DESIGN FOR A STOVE.

SPECIFICATION forming part of Design No. 17,172, dated March 8, 1887.

Application filed January 14, 1887. Serial No. 224,384. Term of patent 7 years.

To all whom it may concern:

Be it known that we, LAZARD KAHN, a citizen of the United States, and RUDOLPH THIEM, a subject of the Emperor of Germany, both 5 residents of Hamilton, Butler county, Ohio, have invented and produced a new and original Design for Stoves, of which the following is a specification, reference being had to the accompanying prints, forming a part hereof.

10 Figure 1 is a perspective view of our newly-designed stove, and Figs. 2 and 3 are views of the respective sides of the cylindrical body portion of the same.

The stove is generally of cylindrical form 15 with a rectangular base.

The leading features by which our design is characterized are as follows: One of the side panels, A, of the stove-body is embellished by a double griffin, B, in relief. The other side 20 panel, A', is embellished by a cupid in a fanciful boat. Both these panels have oval frame-lines. The fuel-door C is embellished by a bust flanked by a pair of vertically-arranged rectangular mica openings upon each side.

25 The ash-door D is of rectangular form, and embellished by a diamond-shaped ornament whose horizontal ends terminate in smaller diamonds, the central diamond bearing an open figure. The supports E for the foot-rail 30 are in the form of bird-talons grasping the rail. The base-door G is embellished by a lyre crossed by a trumpet. The skirting K is embellished by a central heart-shaped panel bearing crossed flambeaux, and flanked by 35 pairs of scrolls placed back to back and joined by a foliated link. The front plate, L, of the body is embellished by an oval panel bearing a flotant scroll and foliated ornamentation. The side pieces of the back flue, M, are embellished by an arabesque study having a central mask in a lower panel and a foliate scroll in an upper panel, a cross-bar separating the two panels. The collar-piece N for the 40 reception of the stove-pipe has its sides in the form of triangular panels ornamented by finely-laid corrugations.

We claim—

1. The design for a stove herein shown and described, comprising the side panels, A A', 45 framed and embellished as shown, the fuel-

door C, embellished by a bust flanked by rectangular mica openings, the ash-door embellished by diamonds and a central oval, the foot-rail in the grasp of supporting bird-talons, the base-door G, embellished by a trumpet-crossed lyre, the skirting K, embellished by a central heart-shaped panel bearing crossed flambeaux, and flanked by pairs of scrolls joined by foliated links, the front plate, L, embellished by an oval panel bearing a flotant scroll and foliate ornamentation, the flue sides M, embellished by an arabesque study and foliate scroll in separate panels, and the collar sides N, in triangular form and ornamented by corrugations.

2. In a design for a stove, the cylindrical body having side panels, A A', with oval frame-lines and bearing the embellishments B B', as shown.

3. In a design for a stove, the fuel-door C, 70 having scroll ornamentation and embellished by a bust flanked by rectangular mica openings, as shown.

4. In a design for a stove, the ash-door D, having scroll ornamentation and embellished 75 by diamonds and a central oval, as shown.

5. In a design for a stove, the side panel having foliate scroll ornamentation and foot-rail supports in the form of bird-talons grasping the foot-rail, as shown.

6. In a design for a stove, the base-door G, 80 embellished by a trumpet-crossed lyre and foliate scroll, as shown.

7. In a design for a stove, the skirting K, 85 embellished by a heart-shaped panel bearing crossed flambeaux and flanked by foliate linked scrolls, as shown.

8. In a design for a stove, the body front plate, L, having scroll ornamentation and embellished by an oval panel bearing a flotant 90 scroll and foliate ornamentation, as shown.

9. In a design for a stove, the flue sides M, 95 embellished by separated panels of foliate and arabesque ornamentation, as shown.

LAZARD KAHN.
RUDOLPH THIEM.
